UNITED STATES PATENT OFFICE.

HENRY L. BARTON, OF PITTSBURG, PENNSYLVANIA, ASSIGNOR TO THE WESTINGHOUSE MACHINE COMPANY, A CORPORATION OF PENNSYLVANIA.

ELASTIC-FLUID TURBINE.

No. 927,445.

Specification of Letters Patent.

Patented July 6, 1909.

Original application filed March 22, 1905, Serial No. 251,421. Divided and this application filed December 17, 1908. Serial No. 468,072.

To all whom it may concern:

Be it known that I, HENRY L. BARTON, a citizen of the United States, and a resident of Pittsburgh, in the county of Allegheny and State of Pennsylvania, have invented new and useful Improvements in Elastic-Fluid Turbines, of which the following is a specification, this application being a division of an application filed by me on March 22, 1905, Serial No. 251,421.

This invention relates to elastic fluid turbines and more particularly to blading for turbines, although it is capable of being utilized in certain types of blowers and compressors.

In the manufacture of turbines, blowers and compressors in which the moving blades and stationary vanes are calked or otherwise secured into annularly-extending grooves or channels provided in the blade and vane-carrying elements, it has been found that the thin edges of the blades and vanes have a tendency to check or crack during the gaging operation. The gaging operation consists in twisting or turning the blades and vanes after they have been secured in place to the blade or vane-carrying element so that the fluid in passing through them will be delivered at the desired angle. This checking or cracking occurs adjacent to the point where the blades and vanes enter the mounting groove or channel and it has been found more or less serious.

One object of this invention has been to overcome the tendency of the blade to check and crack during the gaging operation or after they are in operation in the turbine. While devising means to this end, which, broadly, consists in cutting away a portion of each edge of each blade and vane at a point immediately adjacent to the mounting element, I found that by shearing or otherwise cutting the blades and vanes at the portion adapted to lie within the mounting channel or groove and immediately adjacent to the top of the walls thereof, in the form of a dovetail that I could accomplish the double object of overcoming the tendency to check and crack and also providing means for insuring an extremely rigid connection between the blades and vanes and the elements to which they are attached.

In the drawing accompanying this application and forming a part thereof, Figure 1 is a

partial sectional elevation of a blade-carrying element in which a blade or vane embodying my invention is secured; Fig. 2 is a perspective view of a packing piece embodying my invention; Fig. 3 is a fragmental section of the rotor and stator elements of a turbine in which blades and vanes are secured in accordance with my invention; Fig. 4 is a fragmental transverse section taken on the line A—A of Fig. 3; and, Fig. 5 is a plan view of blades embodied in my invention and mounted in accordance with my invention.

Referring to the drawings: The blade or vane-carrying element 7 of a turbine, blower or compressor is provided with a circumferentially-extending blade-mounting groove 70 or channel 8 in which the bases of blades 9 are secured by means of packing pieces 10. The packing pieces 10 are adapted to be inserted into the channels between adjacent blades and by being transversely expanded 75 are caused to grip the walls of the channels and also the bases of the blades and to thereby secure the blades to the blade-carrying element. In order, as above stated, to insure an extremely rigid connection between 80 the blades or vanes and their respective mounting elements, I undercut the walls of the mounting channels or grooves 8 and shear or otherwise cut away the portion of each blade lying within the channel so as to 85 give it the form of a dovetail. The portion of the edges of the blade outside of the but immediately adjacent to the mounting channels is also cut away and this overcomes the 90 tendency of the blades or vanes to check or crack in the thin edges during the gaging operation. The dovetailed mounting portions of the blades are of such width and so proportioned that when the blade or vane is located within a groove 8 and turned to the 95 desired angle, relative to the axis of the groove, the edges of the base portion of the blade will contact with the side walls of the channel and aid in positively locking the blade to the carrying element. It will be 100 seen that by turning the blade to an unusual position it may be inserted or withdrawn from the channel.

In Fig. 2 I have shown a perspective view of a calking and spacing piece as it appears before it is transversely expanded. In Fig. 3 I have shown sections of two pieces after they are transversely expanded and secured

into the grooves 8. As it is desirable to draw or extrude these calking pieces and thereafter to cut the same into suitable lengths and since it is necessary to so construct each piece that it will completely fill the portion of the mounting channel in which it is located after it has been transversely expanded, I provide a ridge 12 along the top and a depression 13 along the bottom of each piece. Such a construction permits of drawing or extruding the piece in long strips and also provides a piece that will accomplish the desired object. Each piece is provided with one concave face which corresponds in contour to the convex face of the blades and one convex face which corresponds in contour to the concave face of the blades. The pieces are located between the blades in a slot and by being subjected to a transverse pressure are expanded so that their lateral faces are forced into gripping contact with the adjacent walls of the mounting slot and so that their curved faces are caused to grip and hold securely the adjacent faces of the blades. This construction securely and positively locks the blades in place and also prevents checking and cracking at the edges of the blades.

In the accompanying claims I shall refer to "blade-holding elements," but it is to be understood that the word "blade" is used in its broadest sense so as to include the blade of a rotor or the vane of a casing.

In accordance with the provisions of the patent statutes, I have described the principle of operation of my invention, together with the means which I now consider to rep-

resent the best embodiment thereof, but I desire to have it understood that the means shown is only illustrative and that the invention can be carried out by other means.

What I claim is:

1. In combination with a blade-holding element provided with an undercut groove or channel, a plurality of blades having dove-tailed base portions fitting said groove or channel, and a separate blade spacing member calked into said channel between adjacent blades so as to grip the walls thereof and the base portions of said blades. 50

2. The combination with a blade-holding element provided with an undercut groove or channel, a plurality of blades having their base portions cut away to conform to said channel, and spacing members between adjacent blades to be spread by means of pressure so as to grip the walls of the channel and bases of the blades. 55

3. In combination with a blade-holding element provided with a groove or channel dove-tailed in cross-section, a plurality of blades having their base portions cut away so as to conform to said channel and spacing members between the blades and adapted to be calked or otherwise distorted so as to conform to said channel. 60 65

In testimony whereof, I have hereunto subscribed my name this 15th day of December, 1908.

HENRY L. BARTON.
